UNITED STATES PATENT OFFICE.

PETER F. GREENWOOD, OF CATASAUQUA, PA., ASSIGNOR TO HIMSELF AND THE BRYDEN FORGED HORSESHOE WORKS, (LIMITED,) OF SAME PLACE.

MANUFACTURE OF HORSESHOES.

SPECIFICATION forming part of Letters Patent No. 320,349, dated June 16, 1885.

Application filed July 21, 1884. (No model.)

To all whom it may concern:

Be it known that I, PETER F. GREENWOOD, a subject of the Queen of Great Britain and Ireland, residing in Catasauqua, Lehigh county, Pennsylvania, have invented certain Improvements in the Manufacture of Horseshoes, of which the following is a specification.

My invention consists of an improved method or process, fully described and claimed hereinafter, of economically manufacturing horse-shoes.

In the accompanying drawings, Figures 1 and 2, Sheet 1, are views of the rolls, by which the first step or branch of the process is carried into effect; Fig. 3, a perspective view of the crude bar as it appears before being subjected to the rolls, Figs. 1 and 2; Fig. 4, a view of the blank formed by thus passing the bar between the rolls; Fig. 5, a section of the blank, Fig. 4, on the line 1 2; Fig. 6, a section of the blank on the line 3 4; Fig. 7, Sheet 2, a plan view showing mechanism for conducting the second step of the process—that is, the bending of a section, Fig. 4, of the rolled bar; Fig. 8, a perspective view of the blank bent into the form of a horseshoe; Figs. 9, 10, 11, 12, and 13, Sheet 3, views of the drop-press dies by which the third branch of the process is conducted, Fig. 9 being an inverted plan 30 view of the upper die, Fig. 11 a section of Fig. 9 on the line 5 6, Fig. 10 a plan view of the lower die, Fig. 12 a section of Fig. 10 on the line 7 8, and Fig. 13 a vertical section of the two dies; Fig. 14, a perspective view of the 35 shoe-blank after being subjected to the action of the drop-press dies; Fig. 15, a perspective view of Fig. 14 inverted; Fig. 16, Sheet 4, an inverted plan of the upper trimming-die; Fig. 17, a plan view of the lower trimming-die; Fig. 18, a section of the trimming dies on the line 10 11, Figs. 16 and 17; Fig. 19, a section of the same dies on the line 12 13; Fig. 20, a perspective view of the completed shoe; Fig. 21, a perspective view of the same inverted, and Fig. 22 a perspective view of the toe end 45 of the shoe.

Referring in the first instance to Figs. 1 and 2, Sheet 1, A and B are two rolls, the latter having a simple groove, b, and the other having segmental projections a, situated in the re-

lation to each other shown in Fig. 2, the projection being arranged to pass freely into the groove of the lower roller, and each projection having a segmental rib, d. When a bar, D, Fig. 3, has passed between the rolls, it will 55 assume the form shown in Fig. 4—that is to say, there will be depressions e e at intervals formed by the segmental projections a of the upper roll, A, and at the bottom of each depression there will be a recess, f, formed by the 60 segmental rib d of the upper roll. The rolled bar, which may be fifteen or twenty feet long, is now cut into sections by severing it at intervals on the lines x x, Fig. 4, each section having the central projection, h, and opposite 65 end projections, i i, and forming the blank M, resulting from the first step of the process. It should be stated here that the central and end portions of this blank are of the same width as the original bar and slightly narrower than 70 the depressed portions of the bar, which have been distended laterally by rolling, in order that these projections, which are to form the toe and heel calks, may readily enter the openings in the die in the drop-press, as hereinafter 75 described. Furthermore, by thus making the bar narrowest from y to y, Fig. 4, the bending of the blank during the next step of the process is facilitated.

The mechanism which I employ for bending the above-described blank is well known to those skilled in the art to which my invention relates; hence a brief description in connection with Fig. 7 will suffice here. A disk, E, on a shaft illustrated by a dotted circle in the said 80 figure, has a projection, F, which conforms to the shape of the inner edge of the shoe, and to the outer edge of the disk is secured a cam, G, for bearing against a roller, m, on one arm of the bell-crank lever H, which is pivoted at 85 p, a roller, n, being carried by the other arm of the bell-crank lever. The blank M (shown by dotted lines, Fig. 7) is held by a set-screw, q, against the projection F near the point of the same, and as the disk is turned partly round 90 the roller n presses the blank against the said projection F, as determined by the action of the cam G on the roller m of the bell-crank lever, the disk being turned back after completing the bending.

Fig. 8 shows the completed bent blank N, of which the end projections, *i i*, of the above-mentioned section M of the bar form the crude calks, and the central projection, *h*, the toe.

5 Referring now to Figs. 9, 10, 11, and 12, the lower die, I, Fig. 12, has a recess, *t*, to conform with the shape of the under side of the finished shoe, and in this recess are small dies *u* for making the depressions for the nail-holes, 10 the upper die, I', having an enlargement, *v*, with inclined edges *ww*, which form the usual bevel in the upper surface of the shoe at and near the inner edge of the same. When the bent blank N has been subjected to the action 15 of these drop-press dies, it will be in the condition shown in Figs. 14 and 15—that is to say, there will be a complete shoe with fins of superfluous metal, and these fins are removed by the dies shown by Figs. 16, 17, 18, and 19, 20 Sheet 4, which need not be described, as they are substantially the same as those used for the same purpose and well known to those skilled in the art. By the action of these dies a merchantable shoe, Figs. 20 and 21, is completed, 25 nothing remaining to be done to this shoe except the piercing of the same for the nails at the points determined by the indentations made by the small dies *u u*, Figs. 10 and 12. If a toe-piece or clip, *c*, Fig. 22, is required, 30 it may be made by hand or mechanism before employed for the purpose.

I may state in conclusion that I have been engaged for several years in the manufacture of horseshoes and the machinery therefor, and that shoes can be made at a cheaper rate by 35 the above-described succession of operations than by any process within my knowledge.

I do not claim in this application the improved blank shown in Figs. 4, 5, and 6, as this forms the subject of a separate application for a patent filed by me February 19, 1885, Serial No. 156,393.

I claim as my invention—

The within-described mode of manufacturing horseshoes, the said mode consisting of 45 the following successive steps, namely: first, rolling a bar, D, to the condition shown in Fig. 4; second, severing the bar into sections M; third, reducing each section to the bent blank N; fourth, drop forging each bent blank, 50 and, fifth, removing the fins from the said blank, all substantially as set forth.

In testimony whereof I have signed my name to this specification in the presence of two subscribing witnesses.

PETER F. GREENWOOD.
